CLAIM

I claim the ornamental design for a combined hair extension package, as shown and described.

DESCRIPTION

FIG. 1 is a front view of the hair extension package showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof; and,

FIG. 8 is an exploded view thereof, showing my design.

1 Claim, 8 Drawing Sheets

FIG. 1

FIG. 3
